his ATTORNEY

UNITED STATES PATENT OFFICE.

JACOB GOLDFARB, OF BROOKLYN, NEW YORK.

REMOVABLE DENTURE.

Application filed January 6, 1925. Serial No. 770.

This invention relates to removable dentures and has for its primary object and purpose to provide simple and effective means for securely holding the denture in place between the natural teeth, and yet permitting of its easy and quick removal so that all parts thereof can be easily cleaned.

The invention comprises metal plates cast to conform with the surfaces of the natural teeth with which said plates are adapted to be engaged and covering the inwardly sloping or undercut opposed faces of the spaced natural teeth, and also extending in whole or in part over other faces thereof to hold the same thereto. Between these plates a saddle member in which the artificial tooth is securely fixed is adapted to be inserted, the opposite side faces of said saddle having a coacting action with the surfaces of said plates.

It is also an additional object of the invention to provide a bridge connection between the cast metal abutment plates.

With the above and other objects in view, the invention consists in the improved removable denture, substantially incorporated in the subjoined claims, embodiments of which will be in the form, construction and relative arrangement of its several parts as will be hereinafter more fully described, and illustrated in the accompanying drawings.

In the drawings, which illustrate only one of the many different forms in which my present improvements may be exemplified and wherein similar reference characters designate corresponding parts throughout the several views:

Figure 1 is a vertical sectional view illustrating a simple and practical embodiment of the invention showing the denture in applied position;

Figure 2 is a plan view of Figure 1;

Figure 3 is a horizontal section on line 3—3 of Figure 1;

Figure 4, Figure 5 and Figure 6 are perspective views showing the several parts of the device in separated relation;

Figure 7 is a perspective view of the bridge connection, and

Figure 8 is a modified form of attachment.

For the purpose of showing one adaptation of the invention, I have illustrated in Figure 1 of the drawings, two natural teeth 5 and 6 held in the gum 7 by their roots and spaced from each other owing to the removal of the tooth which was interposed therebetween. It has heretofore been the practice to secure an artificial tooth in this space by means of a dental bridge. Such bridges, however, are more or less difficult to construct and when applied are permanent so that the artificial tooth cannot be readily removed. It is my purpose to provide in lieu of such a dental bridge as heretofore employed, an easily and quickly applied or removable denture consisting of few parts of relatively simple construction, as will more fully appear from the following description.

I provide abutment plates 8 cast from gold, platinum or other non-corrodible acid resisting metal. It will be noted that the opposed faces of the natural teeth 5 and 6 longitudinally of the gum 7 slope inwardly from the ends of the teeth towards the gum as at 9. In other words, the tooth is of appreciably less thickness at the surface of the gum ridge than at its end. The abutment plates 8 are cast in conformity with accurate impressions which are first made of the contour of the respective teeth, by means of wax or other suitable material in the usual manner. It will be seen from reference to Figure 2 of the drawing that these abutment plates are of angular form in horizontal plan, having a part which entirely covers the sloping or undercut surface 9 of the tooth, said part of the abutment plate gradually increasing in thickness from the end of the tooth to the gum ridge and exactly conforming to the shape of the tooth face 9 on one side thereof. At its opposite side the plate 8 has a flat or plane surface 10. The other angular portion 11 of the abutment plate extends over and substantially completely covers the inner side face or lingual part of the tooth, as shown in Figure 2, and at its end is tapered or attenuated in thickness as at 12 and extends over one of the tooth corners 21. The vertical edge of the portion of the abutment plate engaged against the tooth face 9 is

100

also attenuated or tapered in thickness, as at 13, and extends over the diagonally opposite corner 23 of the tooth at the buccal face thereof. Each of these abutment plates 8 on both angularly extending portions thereof has its longitudinal edge at the top or occlusal surface of the tooth laterally curved and gradually tapered in thickness to a fine edge as at 14 for engagement over said surface of the tooth, thereby preventing inward, that is, downward or upward movement, as the case may be, of the abutment plates and undue pressure of the same against the gum 7.

15 From Figures 1 and 2 it will be seen that if the tooth indicated by 6 is furthest forward towards the front of the mouth and the center thereof, then its furthest forward surface is known in the practice of dentistry 20 as the mesial surface, that the oppositely disposed surface of the same tooth is known as the distal surface. The part of the tooth facing the tongue is known as the lingual surface and the oppositely disposed surface 25 which faces the cheek is known as the buccal surface. The uppermost surface of the crown is known as the occlusal surface.

Taking these definitions, well known in 30 the art of dentistry, it will be seen that the improved plate has a portion 13 abutting against the buccal surface of the tooth 6, beginning at the buccal side of the corner 23, and extends along the entire distal surface of the tooth 6, and then extends along 35 the lingual surface of the tooth 6 and thereupon at the portion 12 contacts with the mesial surface of the tooth 6, as seen in Figures 2 and 3. That portion of the abutment plate which extends along the distal surface of the tooth 6 is shaped to conform 40 with the configuration 9 of the tooth 6, as is clearly seen in Figure 1. The configuration of the abutment plate, where it contacts with the tooth 6 at 9 being in close fit with 45 the configuration of the tooth itself. The free side of this distal portion of the abutment plate has a plane surface as at 10.

Looking now down upon the occlusal surface of the tooth 6, as in Figure 2, it will be 50 seen that the abutment plate has a portion 11 that begins at the buccal side of the occlusal surface of the tooth 6, and this portion extends along the distal side of the occlusal surface of the tooth 6, and also 55 along the lingual side of the occlusal surface of the tooth 6 until it terminates at the mesial side of the occlusal surface of the tooth 6. In Figure 3 is shown how the ends 60 12 and 13 embrace the diagonal corners of the tooth 6. Those parts of the abutment on the occlusal surface are slightly rounded, as seen in Figure 2.

65 In respect to the tooth 5, considering only the sides of the tooth 5, as in Figure 2, the abutment plate begins at the buccal side of

the tooth 5, at 13, at the buccal side of the corner, extends along in close fit with the configuration of the tooth 5 along the mesial side thereof and then extends along the lingual side of the tooth 5 until it terminates at the distal side of tooth 5, as shown by the character 12, beyond the corner 21.

Looking down upon the occlusal surface of tooth 5, as in Figure 2, a portion of the 70 abutment plate extends from its beginning at the point 13 in the form of the portion 11, beginning at the buccal side of the occlusal surface beyond the corner 23, then along the mesial side of the occlusal surface, then 75 along the lingual side of the occlusal surface and terminates at the distal side of the occlusal surface of tooth 5, at 12, beyond the corner 21. In Figure 3 is shown how the parts 12 and 13 embrace the tooth 5. Those 80 parts of the abutment on the occlusal surface are slightly rounded, as seen in Figure 2.

85 It will therefore be seen that the configuration given to the abutment plate enables a very close fit to be obtained where the abutment plates conform with the opposed surfaces of the teeth 5 and 6, which in respect to tooth 6 is the distal surface and in respect to the tooth 5 is the mesial surface. The opposing side of the abutment plates, as just described, have plane surfaces 10.

90 From the structures described, it will be seen that the abutment plates may be readily applied by a dentist and the spring-acting clips 12 and 13 by their own inherent resiliency snap into position, as shown. They are held permanently in position in close fitting position in respect to the teeth to prevent the food from lodging therein.

95 The artificial tooth 15 is secured within a saddle member 16. As illustrated, this saddle member is of substantially U-shaped form and may also be produced from gold or other metal similar to the abutment plates 8, and is cast in a suitable mold. A central tapering pin 17 rises from the base 100 of this saddle member for engagement through a similarly shaped orifice 18 centrally formed in the tooth 15. The inner surfaces of the saddle member and surfaces of the pin 17 are coated with a suitable cement so that the tooth 15 is permanently and securely fixed in the saddle member. Modification of this tooth holding means may be readily made. The outer side faces 105 of this saddle member have plane surfaces, as shown at 20, to coat with the plane faces 10 of the abutment members 8. It will thus be apparent that when the artificial tooth and saddle member 16 are inserted between the abutment plates 8, the latter are held by the sliding frictional engagement of the side faces 20 of the saddle member with the 110

faces 10 of the abutment plates. The tight sliding fit of the parallel surfaces prevents food from being lodged therebetween. The saddle has a curved portion 19 resting 5 against the curved portion 18 of the abutment plate, on the occlusal surface thereof, as shown in Figure 2. The saddle has along the sides of the parallel surfaces extending portions 19^a embracing the sides of the 10 abutment plate, as shown in Figure 3.

In another embodiment, I preferably connect the two abutment plates 8 by means of a flexible bridge piece 25, as shown in Figure 7, and in dotted lines in Figure 2, also 15 formed from a suitable metal and welded or otherwise permanently connected at its ends with the two abutment plates.

Accordingly, it will be seen that the entire device in reality consists of only two parts to 20 be separately handled. The flexible bridge connection 25 between the abutment plates permits the latter to be readily adjusted and spaced for engagement with the teeth 5 and 6 in accordance with the spacing of the 25 latter.

For purposes of greater security, I provide one or more dowel pins 22 which are adapted to be removably engaged in transverse mating recesses 24 formed in the 30 opposed contacting surfaces of the saddle member 16 and the abutment members 8. Other securing devices may be provided.

By means of the construction above described, it will be understood that when it is 35 desired to remove the denture for the purpose of cleaning the several parts thereof, it is only necessary to first remove the dowel pin 22, if the latter is employed, and then grasp the saddle between the thumb and 40 finger and apply the necessary outward pull so as to release the holding engagement of the saddle member 16 against the abutment plates 8. The latter may then be readily removed by grasping one of said abutment 45 plates and pulling the same away from the tooth on which it is engaged, in which action the bridge connection 25 will readily flex, if it is used. The other abutment plate will of course then become easily disengaged 50 from the other natural tooth. Thus the two parts of the denture can be thoroughly cleaned on all surfaces thereof. Owing to their very simple form, there are but few crevices present in which food particles may 55 find lodgement, and since all parts and surfaces are freely accessible when the device is removed, such accumulations may therefore be readily dislodged. After the parts have 60 been thoroughly cleaned, they can be very quickly replaced in the mouth between the spaced natural teeth in the manner above explained.

I have herein disclosed an embodiment of the invention which I have found to be very desirable and efficient in actual use. The 65

form and construction of the abutment members or plates provide a firm and adequate support for the saddle which includes the artificial tooth so that possible movement of these abutment members by pressure of the 70 teeth in the opposed jaw thereon and cutting or injury of the gum is obviated. Of course, it will be understood that though I have shown but one artificial tooth, in cases where two natural teeth have been removed, the 75 saddle member 16 may be of such form as to receive two or more artificial teeth. The construction and manner of coaction of the several parts in either case would be substantially identical. 80

This invention may be developed within the scope of the following claims without departing from the essential features of the same and it is desired that the specification and drawings be read as being merely illustrative and not in a limiting sense except as necessitated by the prior art. 85

My invention with reference to all the known forms of removable dentures, is distinguished by the fact that it frees the 90 patient of all manipulations on the shape and condition of his teeth, between which an adaptation of my invention is to be inserted. The two plates facing each other, stay in 95 position so tightly that they cannot absolutely be shaken in any way.

This makes entirely clear the following act:—The plates, as we have seen, being in their places are entirely unremovable; the bridge itself is so constructed that, having 100 been inserted, it locks this unremovability of the plates by itself so that these plates cannot be removed as long as the bridge itself is not removed. From this it becomes clear that once the bridge, by itself, locks 105 the plates, and occupies the space between them, the bridge itself is locked between the plates, and in this way, a mutual interlocking is brought about, i. e., the plates lock the bridge between themselves, and the 110 bridge with both its sides adjacent to the edges of the plates, locks the plates. This is one of the advantages of my invention.

I claim:

1. In a removable denture: two abutment members, shaped to conform with the distal surface of the one respectively to the opposed mesial surface of the other one of two spaced natural teeth and entirely covering the said opposing surfaces of the teeth; the 115 said abutment members having projections extending from the before mentioned surfaces around the edges leading to the lingual surfaces, the labial surfaces and the occlusal surfaces of the said natural teeth; the said abutment members having further opposed plane distal respectively mesial surfaces; and a saddle member having an artificial tooth secured therein, adapted to be inserted 120 between the said abutment members so as to 125 130

press them against their respective adjoining natural teeth; said saddle member being adapted to be removed from between the abutment members and on removal of the 5 saddle member the said abutment members being adapted to be removed severally from their respective natural teeth.

2. In a removable denture: two abutment members of angular cross-sectional form 10 each having a part gradually increasing in thickness and with one side face of the abutment member shaped to conform to the inwardly sloping distal surface of the one respectively to the inwardly sloping mesial 15 surface of the other one of the two spaced natural teeth, said portions of the abutment member entirely covering the said tooth surface, and the adjoining portion of the abutment member extending over and entirely 20 covering the adjoining lingual surface of the tooth; the said abutment members having further portions extending from the first mentioned distal respectively mesial surfaces and from the lingual surfaces 25 around the edges leading to the other two not covered vertical surfaces and to the occlusal surfaces of the two natural teeth; and a saddle member having an artificial tooth secured therein, said saddle member 30 being adapted to be inserted between the abutment members, the said saddle member further being adapted to be removed, and on the removal of the saddle member the said abutment members being adapted to 35 be removed severally from their respective natural teeth.

3. In a removable denture: two abutment members adapted for engagement with spaced natural teeth, said members each being of 40 angular form in cross-section and having portions entirely covering the opposed distal respectively mesial surfaces of the natural teeth, and having other portions extending over the lingual surfaces of the respective teeth, the said abutment members being actually shaped to conform to the tooth surfaces and to the before mentioned portions thereof; the abutment members having further plane distal respectively 45 mesial surfaces facing each other; and a saddle member having an artificial tooth secured therein and being provided with a plane mesial and a plane distal surface to 50 coat with the said distal respectively mesial surfaces of the abutment members upon the insertion of the saddle member therebetween; the said saddle member being thus adapted to be removed, and on removal of the saddle member the said abutment members being adapted severally to be removed from their respective natural teeth.

4. In a removable denture: two abutment members, each of angular form and having portions extending over the opposed distal respectively 55 mesial surfaces of two opposed

spaced natural teeth, and having other portions extending over the lingual surfaces, of their respective teeth; a flexible metal bridge connection between the said abutment members to press them apart and against their corresponding natural teeth; a plane distal face at the one and an opposite plane mesial surface at the other abutment member; and a saddle member having artificial teeth secured therein and being provided with plane mesial and distal faces to coat with the aforesaid plane distal respectively mesial faces of the said abutment member, when the saddle member is inserted therebetween; the saddle member being adapted to be removed and on removal of the saddle member the said abutment members being adapted to remove severally from their respective natural teeth.

5. In a removable denture: two abutment members, of angular form and having portions extending over the opposed distal respectively mesial surfaces of spaced natural teeth and other portions extending over the lingual surfaces of the said teeth the said abutment members having further portions extending from the first mentioned distal respectively mesial surfaces and from the lingual surfaces around the edges leading to the other two not covered vertical surfaces and to the occlusal surfaces of the two natural teeth; the two faces of the said abutment members, which are opposite to the tooth touching surfaces being plane and parallel to each other; a flexible metal bridge connection between the said abutment members; a saddle member having artificial teeth secured therein provided with mesial and distal faces to coat with the plane parallel faces of the said abutment members when the saddle member is inserted therebetween so as to produce a bracing action, detachably retaining the saddle member in place and holding the said abutment members in tight hugging engagement with the surface of the natural teeth; and a transversely extending dowel pin adapted to be removably engaged in mating grooves in the abutting faces of the saddle member and of an abutment member, to positively lock the said saddle member in position; said saddle member therefore being adapted after removal of the dowel pin to be removed from between the abutment members, and thereupon the abutment members being adapted severally to be removed from their respective natural teeth.

6. In a removable denture: two removable abutment members shaped to conform with opposed distal respectively mesial surfaces and two spaced natural teeth and entirely covering the side configuration thereof, the said abutment members having opposed distal respectively mesial surfaces substantially plane; a saddle member hav-

ing an artificial tooth secured therein, said saddle member having plane end surfaces adapted to be inserted between and to coact with the said plane surfaces of the abutment members, and when so inserted, adapted to hold the abutment members in position against the teeth contiguous there-

to and said abutment members being adapted to hold the said saddle member in position.

10

In testimony that I claim the foregoing as my invention, I have signed my name hereto.

JACOB GOLDFARB.
